(57) CLAIM

The ornamental design for a portion of an article of footwear, as shown and described.

DESCRIPTION

FIG. 1 is a bottom perspective view of a portion of an article of footwear showing my new design;
 FIG. 2 is a bottom plan view thereof;
 FIG. 3 is a left side elevational view thereof;
 FIG. 4 is a right side elevational view thereof;
 FIG. 5 is a front elevational view thereof; and,
 FIG. 6 is a rear elevational view thereof.

The broken lines showing a footwear upper and periphery in FIGS. 1-6 represent the portions of the design that form no part of the claim. The six inscribed, innermost circles in FIGS. 1, 2, & 5 define the interior boundary of the design. The broken lines showing human forms within the circles also illustrate portions of the design that form no part of the claim.
